GAS TIGHT SEAL

Filed Sept. 5, 1928

Inventor:
Guenther Buechner,
by *Charles V. Yulles*
His Attorney.

UNITED STATES PATENT OFFICE

GUENTHER BUECHNER, OF SCOTIA, NEW YORK, ASSIGNOR TO GENERAL ELECTRIC COMPANY, A CORPORATION OF NEW YORK

GAS TIGHT SEAL

Application filed September 5, 1928. Serial No. 304,141.

My invention relates to gas tight insulating seals and has for its principal object the provision of an improved anode seal for mercury arc rectifiers.

5 In the operation of mercury arc rectifiers considerable difficulty is encountered in maintaining a gas tight joint or seal between the anode leads, the metallic casing and the interposed insulation. The repeated temperature changes between operating and shut down conditions, as well as variations during operation tend to cause unequal expansion and contraction of the metal and insulating parts of the seal whereby leaks often develop between them. In accordance 15 with my invention this difficulty is substantially eliminated by a novel construction of the seal.

In accordance with my invention an insulating compound placed between the anode stem and a surrounding shell is compressed and forced into intimate contact with the surfaces of the stem and shell by the insertion of a metallic cylinder, this metallic cylinder being constricted, and welded to the anode stem at the exposed end in such a way that the leakage path along the anode stem is greatly increased.

The novel features which I consider characteristic of my invention are pointed out in the appended claims. The invention itself however, will best be understood by reference to the accompanying drawing in which the single figure illustrates an anode for a mercury arc rectifier with the seal, made in accordance with my invention, shown in cross section.

Referring to the drawing in detail, 1 illustrates in cross section a part of the mercury rectifier casing. Part 2 is the anode supported on stud 3 which is in turn supported by anode stem 4. The stem 4 is surrounded by insulating material 5 which is preferably an insulating compound composed of mica and a vitreous binder such as glass. This compound is known as micalex and is fully described in Letters Patent of Percy Broadbent Crossley, Reissue 15,727. The insulation 5 and stem 4 are placed inside of shell 6 which is provided with a flange 7 by means

of which it is attached to the rectifier casing. 1. Enough insulating material 5 is used so that the space between 4 and 6 is completely filled and some of the material extends above the edge of shell 6. This assembly is 55 heated until the micalex 5 is plastic. A cylinder 8 of a non-corrosive alloy, preferably a high percentage chromium alloy, is then forced into the micalex so that it is imbedded therein a substantial distance between the 60 opposed surfaces of 4 and 6 but does not completely pierce the insulation. Cylinder 8 has any convenient diameter such that it is imbedded in the insulation 5 between 4 and 6 and has a thickness such that it forces the 65 insulation 5 into intimate contact with the surfaces of 4 and 6 which may have corrugations or grooves therein and compresses the material further, throughout its entire body, to a uniform predetermined density. The 70 cylinder 8 is constricted for a considerable part of its length so that it fits snugly against stem 4 and is welded to this stem at its exposed end. In this manner a gas tight pocket is formed between 4 and 8 so that if a 75 leak starts along the surface of 4 it must travel along both surfaces of the cylinder 8 before reaching the atmosphere. The length of the constricted part of the cylinder 8, in relation to the total length of the cylinder, 80 may be varied to obtain the required compression of the insulation 5.

The shell 6 being exposed to the surrounding air undergoes much less temperature change than the anode stem. There is therefore, less likelihood of leaks developing along its surface than there is of such leaks developing along the anode stem and less precautions need therefore be taken. The cylinder 8 forces the insulation 5 into sufficiently intimate contact with the ridges on the inner surface of shell 6 to prevent leakage.

In order that stem 4 may be kept as cool as possible, cooling fluid is caused to circulate within it. For this purpose it is provided with a recess 9. A reservoir 10 is fastened over this recess by means of flange 11, so that an opening in the bottom of the reservoir 10 registers with the recess 9. A pipe 12, having an outside diameter smaller than the 100

diameter of recess 9, is so mounted that its lower end is near the bottom of the recess and its upper end is within reservoir 10. Reservoir 10 is filled with cooling fluid, which is preferably water, so that the level is above the upper end of pipe 12. In operation automatic circulation of the fluid takes place, down along the walls of the recess and up through the pipe 12.

10 What I claim as new and desire to secure by Letters Patent of the United States, is:

1. A gas tight seal including a core of conductive material, a layer of insulating material surrounding said core, a metallic shell

15 surrounding said insulating material, and a cylindrical member embedded in said insulating material and pressing said insulating material into intimate contact with said core and said shell, said member being attached at its exposed end to said core.

2. An anode seal for mercury arc rectifiers including an anode stem, a shell surrounding said stem, insulation interposed between said stem and shell, and a member surrounding 25 said stem and embedded at one of its ends in said insulation, said end of said member being arranged to force said insulation into intimate contact with said stem and said shell, said member being constricted at its exposed 30 end and welded to said anode stem.

3. A gas tight seal including a core of conductive material, a layer of insulating material surrounding said core, a metallic shell surrounding said insulating material, and a cylindrical member embedded at one of its 35 ends in said insulating material, said end being arranged to force said insulating material into intimate contact with said core and said shell, said member being attached at its 40 exposed end to said core, the opposed surfaces of said shell and cylindrical member being provided with projections which extend into said insulation.

4. In a mercury arc device, an evacuated 45 casing, an electrode stem, a shell surrounding said stem and connected to said casing, a body of insulating material composed of mica and a vitreous binder interposed between said stem and said shell, and means including 50 a cylindrical member adapted to be pressed into said material and between said stem and shell while said material is in plastic condition to force said material into intimate contact with said stem and shell, whereby 55 leakage between said stem and shell into said casing when said material is in solid condition is prevented.

5. A gas tight seal including a core of conductive material, a layer of insulating material surrounding said core, a metallic shell surrounding said insulating material, and a cylindrical member embedded in said insulating 60 material and arranged to compress 65 said insulating material to a uniform prede-

termined density and into intimate contact with said core and shell.

6. An anode seal for mercury arc rectifiers or the like including an anode stem, a shell surrounding said stem, insulation interposed between said stem and shell, and a member surrounding said stem and embedded at one of its ends in said insulation, said end of said member being arranged to compress said insulation to a predetermined density and into gas tight contact with said stem and shell, said member being connected at its exposed end in gas tight relation to said anode stem.

In witness whereof, I have hereunto set 80 my hand this 4th day of September, 1928.

GUENTHER BUECHNER.
